STANDING VALVE EXTRACTOR

Thaddeus J. Broadway, Pampa, Tex.

Application August 30, 1945, Serial No. 613,515

1 Claim. (Cl. 103—180)

1 The invention relates to an extractor for effecting the removal and replacement of the standing valves of pumps generally, and more especially the standing valves of oil pumps; its primary object being to provide one that is comparatively simple and inexpensive in construction and design and, in the use of which, a standing valve may be placed within a pump barrel or casing with ease and dispatch, or removed therefrom, in order to maintain the operating efficiency of the pump, the removal and replacement being readily accomplished without resort to the removal of the barrel or casing.

Another object of the invention has to do with the provision of such an extractor and which is adapted to be detachably engaged with the cage or case of a standing valve for the emplacement of the same on the standing valve body, and to be interlocked therewith in effecting its removal from the latter and its withdrawal from the barrel of the pump.

A further object of the invention lies in the provision of the extractor as hereinbefore characterized and which has the form of a cage-like body, adapted for attachment to the bottom of the traveling valve of a pump, and a grappling member carried by the body and adjustable relatively thereto, to and from one or the other of its two positions of use; the grappling member being adapted to be detachably engaged with the standing valve cage, in effecting the emplacement of the same on the standing valve body, when in one of its positions of use, and to be interlocked with the standing valve cage, in effecting the removal thereof from the standing valve body and its withdrawal from the pump barrel, when disposed in the other position of use.

With these and other objects in view the invention consists in the features of construction, combination and arrangement of parts as will be hereinafter more fully described, illustrated in the accompanying drawing, which shows the preferred embodiment of the invention, and pointed out in the claim hereunto appended.

In the accompanying drawing:

Figure 1 is a vertical longitudinal section through the standing valve and working barrel with the extractor assembly constructed in accordance with the invention in association.

Figure 2 is a view similar to Figure 1 showing interlocked engagement thereof.

Figure 3 is a fragmentary sectional view taken on the line 3—3 of Figure 2 looking in the direction of the arrows.

2 Figure 4 is a sectional view taken on the line 4—4 of Figure 2 looking in the direction of the arrows.

Figure 5 is a sectional view taken on the line 5—5 of Figure 2 looking in the direction of the arrows.

Similar reference characters indicate corresponding parts throughout the several views in the drawing.

10 Referring to the drawings in detail, A designates the top end of an oil well casing and B a pump barrel mounted thereon. A standing valve body 10, provided with a plurality of superimposed packing rings 11 held in place on its lower end portion by a jam nut 12, is positioned in the lower end of the barrel B. The standing valve body 10, above the packing rings 11, is tapered for a portion of its length, as at 17, and terminates in a cylindrical top end portion 17a.

20 Detachably seated on this reduced end portion of the standing valve body 10, is a cylindrical cage-like body 13 housing a valve element 14, preferably in the form of a ball; the lower end of the cage 13 being open and screw threaded onto 25 an annular member 16a connecting the upper ends of a set of equidistantly spaced jaws 16 which engage about the tapered and cylindrical portions of the standing valve body. Fitted within the lower end of the cage 13 and the upper side of the annular member 16a, is a seat 15 for the valve element 14; the seat resting on a flange 16b, encircling the inner side of the annular member, and thus centering the valve opening with respect to the bore extending upwardly 30 through the standing valve body 10. The lower side of the flange 16b is grooved to engage over the top edge of the cylindrical part 17a, of the standing valve body, which edge is preferably beveled, as at 20, to support a gasket 21, in sealing contact with the complementary angle of said groove. The tapered part 17, of the standing valve body, is provided with an annular groove 19 to seat an expansion ring 18, which is adapted 35 to engage in complementary grooves 16c, formed in the inner sides of the jaws 16, to retain the valve cage 13 in place during pump operation and to permit of its disengagement and withdrawal upwardly of the barrel B, when required. The side wall of the valve cage 13 is vertically slotted, as at 13a, and its top end wall is centrally apertured to receive a bushing 35, the bore of the bushing being disposed in line with the valve opening in the seat 15.

40 For accomplishing the objects and purposes of 45 the invention, the extractor takes the form of a 50

55

cylindrical body 23, having its upper end open and screw threaded, as at 23a, for attachment to the lower end of the usual traveling valve (not shown), carried at the lower end of the suction rod (not shown) of a pump. The lower end wall 23b, of the body 23, is also centrally apertured for the vertical adjustment therein of a grappling device, which is comprised in a pin 24, having its upper end headed, as at 24a, and its lower end 24b curvingly tapered and projecting downwardly through the said aperture. Fitted within the body 23, and resting on an annular shoulder 23c encircling the inner side wall thereof, is a cage-like body 25, having a top end wall 26a disposed immediately below the internally threaded portion 23a of the body 23, and a bottom wall 25b disposed in spaced relation with respect to the bottom wall 23b. The wall 25b is centrally apertured for the passage of the pin 24 therethrough, with its headed end 24a housed between the upper and lower walls 25a and 25b, of the body 25, and its lower end 24b, as before stated, depending through the aperture in the lower end wall 23b, of the body 23; the latter end of the pin having an annular groove 33 at the base of the taper thereof to be engaged by an expansion ring 32, carried in an annular groove formed in the bore of the bushing 35, to detachably connect the valve cage 13 with the extractor body 23, when it is to be lowered within the barrel B to seat on the standing valve body 10.

Pivottally mounted in the opposite ends of a slot formed diametrically through the pin 24, immediately below the head 24a, is a pair of latches 28, which are retractably held in projected positions, outwardly of the slot ends, by a spring element 30; and likewise mounted in a second such slot in the pin, at a point substantially midway between the upper slot and the tapered end 24b, is a second pair of latches 29, which are also retractably held in projected positions, outwardly of the slot ends, by a spring element 30.

In the use of the extractor, as thus constructed and arranged, it is to be screw threaded onto the lower end of the traveling valve, or of the suction rod, for the purpose of placing a valve cage 13 in position on the upper end of the standing valve body 10, subsequent to the removal of the same for repair or renewal; it being understood that the valve cage was emplaced on the standing valve body when the parts of the pump were assembled, at the time of the installation thereof.

To remove the valve cage 13 from the standing valve body 10, the pin 24 is positioned relatively to the body 25 with the upper set of latches 28 engaged beneath the lower end wall 25b and the lower set 29 beneath the lower end wall 23b, of the outer body 23, substantially as shown in Figure 2 of the drawings. Now, on the down-stroke of the suction rod, the tapered end 24b, of the pin 24, passes through the bore of the bushing 35, carried in the top end of the valve cage 13, as does the groove 33 and the lower set of latches 29 also, the groove and latches snapping past the expansion ring 32, in the bore of the bushing, to that end. As the latches 29 clear the bore, they are projected outwardly beneath the lower side of the bushing 35, by the expansion action of the spring element 30 associated therewith, so that the extractor and the

5 valve cage 13 are positively coupled together and the latter therefore will be lifted from the standing valve body 10 on the up-stroke of the suction rod, the attaching jaws 16, of the valve cage, snapping free from the expansion ring 32.

10 To replace the valve cage 13 on the standing valve body 10, the pin 24 is positioned relatively to its carrier body 25, with the upper set of latches 28 above the bottom wall 25b and the lower set 29 beneath that wall and between the same and the lower end wall 23b, of the outer body 23. With the pin 24 in this position, the tapered end 24b is inserted into the bore of the bushing 35, in the upper end of the valve cage 13, until the groove 33 is engaged by the expansion ring 32, the retaining effort of which being sufficient to support the valve cage 13 on the down-stroke of the suction rod to seat the latter on the upper end of the standing valve body 10. When seated, the valve cage 13 is retained in place by the expansion ring 32 sufficiently to permit of the freeing of the pin 24 from the holding effort of the expansion ring 32 and the withdrawal of the extractor upwardly of the barrel B, on the up-stroke of the suction rod. Access is to be had to the latch pair 28 by inserting the fingers inwardly through slotted openings 23e formed in the side wall of the body 23 for the adjustment of the pin 24 in the stated manner, the openings being shown in Figure 4, and, in this connection, it is to be understood that the body 25 is removable from within the body 23, when the latter is separated from the traveling valve.

15 35 Having thus fully described a preferred embodiment of my invention, it is to be understood that the words which I have used are words of description rather than of limitation, and that changes within the purview of the appended claim may be made, without departing from the true scope and spirit of my invention in its broader aspects.

20 40 45 What is claimed is:

In combination, a valve body, a cage detachably connected to said valve body, an extractor for moving said cage into and out of engagement with said valve body, a bushing connected to the top of said cage, said extractor including a hollow body, a grappling pin reciprocably carried by said hollow body and having a lower tapered end mounted for movement into and out of said bushing, coacting means on said grappling pin and bushing for selectively maintaining said pin in said bushing, horizontally disposed spaced parallel walls arranged in said extractor, latches pivotally connected to said grappling pin and mounted for movement through said walls into and out of selective engagement with said bushing, and springs for normally urging said latches out of said grappling pin.
